UNITED STATES PATENT OFFICE

2,101,987

PROCESS OF TREATING TEXTILE FABRIC
FOR REINFORCING INSOLES

Elmer A. Ellis, Medford, Mass.

Application August 16, 1934, Serial No. 740,690

1 Claim. (Cl. 12—146)

My present invention is a novel and improved method of treating or coating duck, canvas, or the like textile material to be applied as a reinforcing to insoles, particularly welt insoles for use in the manufacture of boots and shoes.

This reinforcing process, well known as gemming, has long been employed in boot and shoe manufacture. Heretofore two processes have been utilized: The "hot" process, wherein the 10 coating applied to the reinforcing duck and the cement coating applied thereto for attachment to the insole has been put through a steaming or heating process where a relatively high degree of heat is necessary to render the coating "tacky" 15 and enable the reinforcing duck to be applied to and adhere closely to the insole, particularly to the sewing rib and the underseam groove, usually at the base of the rib.

The other method has been the cold process 20 where reinforcing of the insole or gemming has been applied with the cement on the duck, of a cementitious material, which would be "tacky" while cold or at "room temperature".

A constant disadvantage with such material has been the necessity of shipping the same in 25 rolls to a shoe factory after the duck had been coated and to either keep the adhesive in condition for use or to specially treat the coating so that it could be applied to the insoles.

By my present invention I have devised a compact, efficient apparatus and a process whereby the duck to be used for reinforcing or gemming insoles can be coated and slightly heated directly on the job and applied to the insoles to be reinforced.

Preferably also I provide my apparatus with means for treating two strips of duck simultaneously, thus doubling the normal capacity.

Furthermore, an additional novelty in the present invention consists in the arrangement whereby I am enabled to apply two coatings to the duck on its passage through my apparatus, thus utilizing plain unsized canvas and treating and coating it with suitable adhesive which, for this purpose, is maintained in a perceptibly heated state, viz: substantially above any "cold" process or "room temperature" methods, such as shown in my prior Patent No. 1,830,534, dated November 3, 1931, but which temperature is not of any relatively high degree. High temperatures involve danger of fire, explosion, etc., and by my present invention I am enabled to obtain all the advantages incident to a heated gemming process, which greatly facilitates the "set" of the canvas, particularly at the base of the sewing rim, where it is most

important, without the fire risk and danger heretofore incident to a heated process.

This method of double coating enables me to utilize extremely inexpensive duck while treating and coating it "on the job", giving a sizing if necessary and then an adhesive coating or applying two thin adhesive coatings just prior to the gemming operation.

Other advantages, important features, and combinations will be hereinafter more fully pointed out and claimed.

Referring to the drawings illustrating preferred embodiments of my invention,

Fig. 1 is a plan view with a portion of the cover or top broken away illustrating my improved 15 apparatus;

Fig. 2 is a side view;

Fig. 3 is a cross-sectional view on the line 3—3 of Fig. 2.

Fig. 4 is a fragmentary detail on the line 20 4—4 of Fig. 5, showing the guides for the canvas strips fed through the machine, and

Fig. 5 is a side view illustrating the double treating machine, wherein duplicate applying and treating devices are arranged in combination. 25

As shown in the drawings, I designate the frame or base of my machine adapted to be fitted on a bench or any suitable support adjacent the insole gemming station in a shoe factory. Preferably, this base is of sufficient depth to contain water, which is heated by an electrical heating unit 2 receiving current from any suitable source of supply. The base 1 has a lateral extension 3, with a cored recess designated at 4 opening into an upstanding holder 5 which is 30 fitted to receive an inverted latex bottle and, by vacuum feed, permit a continuous supply of latex and at a predetermined level at the base of the receptacle 10.

I prefer to form the base 1 of sufficient depth 40 to constitute both a water-receiving receptacle and to support and hold a cement- and roll-receiving boxlike structure 10, which will have the lower portion immersed below the normal level of the water within the base 1. This member 10 is provided with extending lugs 6—6 and 7—7 arranged in pairs to overlap the side edges of the walls of the base 1 (see Fig. 3), which lugs also constitute means for attaching and locking the upper part or heated cover of my apparatus. 45 50

Within the member 10 I mount a set of supports or bridges 12—12 connected by a central cross-bar 14 to hold the same in suitable spacing and with grooves formed therein to receive the axles 15 of feed rolls 20 and 21. In this member

10 is put a quantity of resinous emulsion, vulcanized latex, which is fed to the canvas as it passes over the feed rolls, as will be explained. Fitted also within the member 10 is a stripper plate 25 to remove surplus coating material from the canvas before it passes out from within the area of the box 10. Removably secured to the box 10 is a top or cover 30, having thin heat transmitting plates 31 and 32, and a heating coil 33 contained therein receiving heat from any suitable source of supply. On the lower portion 32 is affixed a pressure member 35, of semi-cylindrical contour, midway between and depending below the top portion of the rolls 20 and 21. I also affix to the cover 32 a spring-pressure member 36 to cooperate with the stripper member 25 to press against the opposite and uncoated surface of the canvas as the same is fed through the apparatus.

To hold the cover 30 in position I form the same with a pair of outwardly extending lugs 40-40 at the front of the machine, to which are pivoted threaded locking clamps 41-41, having a pair of thumb nuts 42 and 43 adapted to engage the lugs 6 on the box 10, said lugs being slotted for this purpose as shown at 44. Manipulation of the thumb nuts 42 and 43 thus not only serve to lock the top member 30 to the box 2 but also afford capacity for adjustment of the same and hence of the bearing members 35 and 36. Attached to the cover 30 opposite the lugs 40 are a pair of depending arms 46 having trunnions 47, 47 resting in recesses in the lugs 17, 17, as clearly shown in Figs. 2 and 3.

Preferably I form the cover 30 with a straight flat portion where it extends from the width of the box 10 and within the bevelled or inclined portion to the left (viewed in Figs. 3 and 5) to facilitate the travel of the canvas 50. At the front of the machine (viewed in the right of Figs. 3 and 5) I apply to the cover portion 30 a guide roll 53 mounted on axles 54 in bearings in the cover, as shown.

On the base 1 at the left of the machine, viewed in Figs. 3 and 5, a feed roll 56 is fitted in brackets 57 on the base 1 and a cooperating feed roll 58 is fitted on the brackets 7 attached to the box 10. The cover 30 may be released by loosening the locking nuts 42 and 43, whereupon the levers 41 are swung out of the grooves 44 and the entire cover lifted upwardly. Thereupon the canvas 50 is led through the machine in the direction of the arrow, Fig. 3, over the guide rolls 56 and 58 across the tops of the feed rolls 20 and 21 and, thereupon, the cover 30 is lowered and the canvas 50 led from the guide roll 53 and across the plate 31 of the cover extending downwardly in the direction of the arrow to convenient reach of the workman.

This operation also acts to force the pressure member 35 and spring pressure member 36 in contact with the canvas 20, the former depressing the strip below the level and in intimate contact with the tops of the feed rolls 20 and 21, while the spring 36 holds the canvas in intimate contact with the top of the stripper plate 25. Preferably the first feed roll 20 will be provided with a series of transverse grooves or corrugations to facilitate carrying up the heated solution to apply to the contacting surface of the canvas belt 50; while the second feed roll 21 will largely produce a smooth and spreading action, which is completed by the stripper 25 which also removes surplus material to fall back into the bottom of the box 10.

75 The belt 50 is then led over the roll 53 and re-

versely across the heated plate 31 in contact with the same, thus effecting a substantially instantaneous setting of the material, latex, or the like, fed to the opposite surface of the belt 50 in its passage over the feed rolls 20 and 21.

With the apparatus as thus far described, it will be appreciated that the heating unit 2 will bring the water in the base 1 to any desired temperature. I find that for such an immersion heater, a unit of thirty watts capacity is sufficient. Under the heating unit 33 a capacity of forty watts is sufficient. A high heat service can be given to the heater 33 if it is desired to feed through the belt 50 at greater speed than is customary in order to effect the setting of the 15 solution on the belt 50 in a shorter time.

As thus far described, it will be appreciated that the canvas strip or belt, preferably of un-sized and uncoated material, is fed through the apparatus and the heated emulsion is applied thereto by the feed rolls 20 and 21. I find that a temperature of approximately 100° F. is ample for this purpose in view of the subsequent heating and setting. The belt 50 is fed through either continually or intermittently by hand, as the operator may pull off a strip from the delivery end of the cover 30, coat same, and apply it to the insole.

This operation will give sufficient time for the setting of a corresponding section of the belt 30 which has now been pulled into position over the heated plate 31. The operation is repeated and continued.

Preferably I arrange the apparatus of sufficient width to take two belts, as shown in Fig. 2, so that one operator can work on each side, if desired, and pairs of shoes can be gemmed simultaneously.

In Fig. 4 I have illustrated a slight modification in which the heated plate 60 is here shown 40 with a pair of guiding rims 61 on each edge, thus facilitating the travel of the belt 50 over the heating plate as well as guiding and giving a frictional grip on same.

In Fig. 5 I have illustrated a double unit where- 45 in successive coatings are applied to the same surface of the belt 50. For this purpose I duplicate the construction of the feeding and heating devices, as above explained, but showing the first heating member 65 in a cover 66 which is 50 horizontal in position and is provided with a guide roll 68 mounted in a pair of upstanding lugs 67 on one edge of the machine, to the left viewed in Fig. 5, around which the canvas belt or strip 50 is led upwardly to the first guide roll 55 55 on the second coating machine.

By this arrangement, also, I may prefer to mount the top member 1 directly upon but spaced from the lower member by means of a set of four posts 70 passing through appropriate 60 holes or recesses in the base flanges 71 of the upper tank 1 into sockets in the flanges 72 of the lower part in the bottom member with spacing tubes 74 on which the upper unit may rest. The action of each unit is identical and the heating member 65 may be of sufficient power, such as eighty watts, to effect a more thorough drying of the first coat before the same surface of the belt 50 is treated to a second coat. Furthermore, this first coat may be a "priming" or sizing 70 of any desired material or consistency, while the second coating is preferably of a latex emulsion and is mainly for adhesive purposes to attach the reinforcing canvas onto the insole.

I believe that my method of thus making and 75

coating a strip, or plurality of strips, of canvas for insole reinforcing, by applying latex or other material directly to one surface, instantaneously setting it, and all at a relatively slight degree of heat, viz: 110° F. or somewhat greater, is a distinct novelty and improvement in this art. I also believe that the application of a plurality of coatings in the manner described is new and, therefore, I wish to claim the same herein broadly.

Furthermore, my compact, simple, economical apparatus is neat, clean, and operates at a degree of heat which eliminates risk and danger of fire, explosion, or the like, as well as absolutely preventing any damage to the leather on which the reinforcing layer is applied, and I believe the same is new and useful and, hence, wish to claim the same.

I claim:

That improvement in the method of reinforcing insoles by applying fabric thereto, which consists in conducting a continuous strip of uncoated and unsized fabric thru successive treating and drying operations as an immediate step in applying the reinforcing to insoles, said treating and drying being in immediate sequence as a substantially simultaneous action at relatively high speed, said treating consisting of applying a liquid sizing and adhesive to one surface only of the fabric strip, and thereupon reversing the line of travel of the now-treated strip, and conducting the same with the untreated surface in contact with a heated plate, whereby the fabric is treated, partially dried, and rendered tacky for immediate use in reinforcing insoles.

ELMER A. ELLIS.
